UNITED STATES PATENT OFFICE.

MOSES C. JOHNSON, OF HARTFORD, CONNECTICUT, ASSIGNOR TO THE HELIX GEAR COMPANY, OF SAME PLACE.

DESIGN FOR A BICYCLE-FRAME.

SPECIFICATION forming part of Design No. 31,319, dated August 1, 1899.

Application filed July 5, 1899. Serial No. 722,877. Term of patent 14 years.

To all whom it may concern:

Be it known that I, MOSES C. JOHNSON, a citizen of the United States, and a resident of Hartford, in the county of Hartford and State of Connecticut, have invented a new and original Design for a Bicycle-Frame; and I do hereby declare the following, when taken in connection with the accompanying drawings, to be a full, clear, and exact description of the same, and said drawings constitute part of this specification, and represent, in—

Figure 1, a view in side elevation of the frame; in Fig. 2, a view in front elevation of the essential feature at the lower part of the frame, and in Fig. 3 a view in rear elevation of the said essential feature.

My invention relates to a design for the frame of a bicycle in which there are upright parts, as *a b*, inclined members, as *c d*, and substantially horizontal members, as *e f*. The two members *a d* at their lower ends unite with a circular member *g*, and the inclined rear member *c* terminates in a circular member *h* as the parts appear when viewed in elevation

from the side, as in Fig. 1. Below the member *g* is a cylindrical member *g'* with its axis placed transversely of the axis of the cylinder *g*, and a like cylinder *h'* underlies the cylinder *h*, these parts *g' h'* being connected by the frame member *f*. The members *c* and *f* are, in fact, rear forks of the bicycle-frame, and the parts *g' g h h'* are the crank-hanger and gear-casings.

The essential feature of the design resides in the substantially offset arrangement of the frame member *f* with reference to and below the casings *g* and *h*, the lines of this member *f* being located outward from the center of the parts *g* and *h* as distinguished from a line which passes through the center of said parts.

Having described my invention, what I desire to secure by Letters Patent is—

The design for a bicycle-frame substantially as herein shown and described.

MOSES C. JOHNSON.
